HIS ATTORNEY.

UNITED STATES PATENT OFFICE

2,273,308

JOURNAL BOX

Otto W. Young, Maplewood, N. J., assignor to
General Motors Corporation, Detroit, Mich., a
corporation of Delaware

Application September 27, 1940, Serial No. 358,612

2 Claims. (Cl. 308—41)

This invention relates to journal boxes and comprises all of the features of novelty herein disclosed. An object of the invention is to provide improved devices for absorbing end thrust of a journalled shaft, especially an axle in a railroad journal box. Another object is to provide a simple, compact and inexpensive thrust construction for journal boxes. Another object is to provide an improved thrust construction wherein the thrust block self-aligns itself with the axle. To these ends and also to improve generally upon devices of this character, the invention consists in the various matters herein-after described and claimed. In its broader aspects, the invention is not necessarily limited to the specific construction selected for illustrative purposes in the accompanying drawing in which

Fig. 1 is a vertical longitudinal section through the outer portion of a railroad journal box.

Fig. 2 is one half a horizontal section and one half a plan view of Fig. 1, the cover of the box being removed.

The numeral 10 indicates the outer or front portion of a railroad journal box having pedestal flanges 12 at the sides. An outer raceway sleeve 14 in the box carries roller bearings 16 which also run on an inner raceway sleeve 18 pressed on a shaft or axle 20. The outer or front end of the box has an integral end wall 22 spaced from the end of the axle and terminating at the top at an inclined pad 24 surrounding an opening closed by a cover 26 removably fastened by screw bolts. A shelf or pan 28 having a bottom drain opening projects towards the bearings to collect oil from the delivery portion of a lubricant collecting ring 30. The ring 30 has its bottom wall 31 and its side walls 32 extended to the end wall 22, its side walls being secured by bolts 33 to the end wall 22. The foregoing structure is similar to that of the Gibbons Patent 2,133,024 and constitutes the environment in which the present improvement is embodied and for which it is especially adapted.

A holding plate 34 which is externally substantially square has its vertical side walls fitting freely between vertical internal side faces 35 in the side walls 32, removable spacing plates 36 being interposed between the holding plate and the end wall 22. The spacing plates 36 are externally square and internally round. Other spacing plates 38 of inverted U-shape are interposed between the holding plate and forwardly facing shoulders on the side walls 32. The holding plate and the spacing plates rest at the bottom on horizontal ledges or pads 40 on the bottom wall 31,

the spacing plates being just sufficiently loose so that they can be lifted out of the box when the cover 26 is removed, without loosening of the bolts 33. The holding plate is however substantially fixed or anchored with respect to the end wall 22.

Extending towards the axle, preferably as a part of the holding plate, is a hollow circular projection 42 which is internally cylindrical. Externally the projection is cylindrical for a portion of its length and the remainder is convexly rounded or tapering to the end as indicated at 44. Fitting tightly around the cylindrical portion of the projection so that it is internally confined and stretched is a resilient pad in the form of a substantially cylindrical cushioning ring 46 which can be of rubber or similar material such as "Neoprene." The resilient ring seats or abuts at one end against the flat face of the holding plate 34 and at the other end against a flat face on a thrust block 48 having a thrust surface 50 which is normally spaced from the axle but is intermittently engaged by the axle whenever the latter shifts endwise. The thrust block has a hollow exterior projection 52 which is internally cylindrical for a portion of its length and convexly rounded or tapered towards the end, the projection tightly surrounding a portion of the resilient ring and radially confining its outer surface under compression. Externally the projection has vertical faces 53 to co-operate with vertical interior faces on the side walls 32 to prevent rotation of the thrust block but there is clearance between these faces. The projections partially telescope to produce compactness.

The upper portion of the thrust block has the usual extension 54 with a finger or tool hole for lifting it and it also has an oil collecting cavity 55 leading to an inclined drain opening 56 which supplies the thrust surface with lubricant.

Welded to the thrust block is a tension bar in the form of a sleeve 58 which projects with appreciable clearance through the projection 42 to a point adjacent to the end wall 22. The sleeve has a groove to receive a split ring 60 which engages the holding plate and holds the resilient ring under an initial compression axially. The connected parts handle as a unit and can be removed as a unit from the box by vertical movement and a slight tilting after the cover 26 and the spacing parts 36 have been removed. The projection 42 supports the resilient ring and the resilient ring supports the thrust block, the thrust block having clearance with the ring 30. The axial compression or preload keeps the thrust block from tilting under its own weight and get-

ting unnecessary rubbing by the rotating axle when the latter is near its central or neutral position. The thrust block can universally tilt and self-align its thrust surface with the axle however when the preload is overcome by sufficient endwise thrust caused by endwise shifting of the axle. Pressure applied endwise will cause the resilient ring, as it deflects, to become increasingly confined radially. As the ring becomes more confined, the load necessary to cause more deflection will increase. Thus the resistance to deflection will increase with movement of the thrust block and become a maximum at full deflection. The tapered or rounded surfaces let the rubber deflect without cutting into it. The cushioning unit is very compact due to the partial telescoping of the various parts and it is wholly confined in the space between the end of the shaft and the end wall.

I claim:

1. In a device of the character indicated, a journal box, a shaft journaled in the box, the box having an end wall extending across and spaced from the end of the shaft, a thrust block interposed in the space between the shaft and the end wall, and means for supporting the thrust block for self-aligning cushioned movement with respect to the shaft, said means comprising a pair of circular confining surfaces projecting one with-

in the other from the thrust block and the end wall, portions of said surfaces being cylindrical and the terminal portions being convexly rounded, and a resilient cushioning ring having internal and external cylindrical surfaces confined radially under initial compression for a portion of its axial extent by said cylindrical surfaces of the projections and adapted to be radially compressed over increasing portions of its axial extent by 10 said convexly rounded terminal portions as the thrust block is forced towards the holding plate by the shaft.

2. In a device of the character indicated, a thrust unit comprising a thrust block and a connected holding plate, each having flat abutment faces opposed to one another and projections of different diameter extending one within the other from the abutment faces, a resilient cushioning ring having internal and external cylindrical portions radially confined under initial compression by the projections, the ends of the ring being flat, and means for limiting separation of the holding plate and the thrust block and comprising a tension bar projecting from one of said members through the other for causing the abutment faces to forcibly engage said ends of the ring to hold the ring under initial axial compression.

OTTO W. YOUNG.
